UNITED STATES PATENT OFFICE.

HENRY W. MORGAN, OF ROCHESTER, NEW YORK.

NAILING-MACHINE.

SPECIFICATION forming part of Letters Patent No. 696,466, dated April 1, 1902.

Application filed March 10, 1899. Serial No. 708,585. (No model.

To all whom it may concern:

Be it known that I, HENRY W. MORGAN, of Rochester, in the county of Monroe and State of New York, have invented certain new and useful Improvements in Nailing-Machines; and I do hereby declare the following to be a full, clear, and exact description of the same, reference being had to the accompanying drawings, forming a part of this specification, and to the reference-numerals marked thereon.

My present invention relates to nailing-machines particularly adapted for nailing the tops upon round articles, such as tubs for containing butter or similar material; and it consists in certain improvements and adjustable parts whereby tubs or other round receptacles of various sizes may be operated upon, all as will be hereinafter fully described, the novel features being pointed out in the claims at the end of this specification.

In the accompanying drawings, Figure 1 is a perspective view of a machine embodying my improvements; Fig. 2, a horizontal sectional view taken just above the nail-holding chucks. Fig. 3 is a vertical sectional view of the head of the machine, showing the nail-channels and picking or selecting devices; Fig. 4, a vertical sectional view of one of the nail-holding chucks; Fig. 5, a sectional view on the line *c c* of Fig. 4; Fig. 6, a horizontal sectional view taken on the line *d d* of Fig. 5; Fig. 7, a side view of one of the chucks; Fig. 8, a sectional view taken on the line *e e* of Fig. 2; Fig. 9, a sectional view on the line *ff* of Fig. 2.

Similar reference-numerals in the different figures indicate similar parts.

1 indicates the main frame or standard of the machine, having at the sides vertical ways 2, upon which slides the table or work-support 3, moved vertically by a screw 4, adapted to be actuated by suitable gearing from a hand-wheel 5, extending from the side, as shown.

6 indicates a suitable sliding cross-head carrying the nail-driving devices, also sliding upon the ways 2 of the main frame and adapted to be reciprocated vertically by a pitman 50 and mechanism for operating it or other form of reciprocating device—such, for instance, as shown in my prior patent, No. 586,711, and

therefore not needing specific description herein. The cross-head 6 is provided with the dovetail projection 7, upon which are mounted forwardly-extending brackets or arms 8, adjustably secured in position upon the head by bolts 9 or otherwise and having the slots or recesses 10 in their under side for the reception of the laterally-extended heads 60 of the nail drivers or punches 11, said drivers passing through the nail-holding chucks supported below them, as will be presently described. Formed upon the sides of the arms or brackets 8 are ways 12, and coöoperating 65 with said ways and with the under sides of the brackets are small laterally-extending driver-brackets 13, adjustable upon the brackets 8 and adapted to be secured in position thereon by bolts 39 or otherwise and provided with 70 the T-shaped slots 14 in their lower sides for the reception of the heads of drivers or punches 15, which latter are adjustable in said slots longitudinally of the brackets 13. Arranged upon the main frame beneath the 75 sliding cross-head is a dovetail cross-bar 16, and mounted upon this are laterally-adjustable brackets 17, adapted to be secured in position by bolts 18 or otherwise and having the forwardly-extending chuck-supports 19 80 thereon, said supports being composed of two parallel rods or bars rigidly connected at their outer ends by blocks 20 or otherwise.

21 indicates nail-holding chucks constructed substantially as shown in my prior patent, 85 No. 587,321, having the angular rearward projections 22, adapted to fit in the slot between the bars constituting the supports 19, and having also the bolt 23, by which said chucks are clamped to the arms when in adjusted position. In the present embodiment two of these chucks are shown located at the inner and outer ends of the supports 19, and the chucks nearest the main frame or standard being provided with the downward 95 extensions 24, having the adjustable abutments 25 thereon to coöperate with the rear side of the tub or keg operated upon and indicated by T, so as to center and hold it in proper position. 26 indicates L-shaped 100 chuck holders or brackets arranged to slide upon the outer sides of the arms 19, having the angular projections fitting the space between said arms and secured in adjusted po-

sition by nuts or bolts, (shown particularly in Fig. 2), said chuck holders or brackets 26 being slotted and adapted to receive adjustable nail-chucks 27, similar in essential parts 5 to the chucks 21 and adjustable on the supports toward and from the arms 19.

Each of the chucks is provided, as usual, with the driver-passage 28, nail-passage 29, and spring-operated jaws 30, the front or 10 outer portion 31 of said chucks being adapted to yield outwardly against the tension of springs 32 should a nail become clogged in the channels, as shown in my last-mentioned patent. From the construction shown it will 15 be seen that the nail-chucks 21 and 27 can be so relatively adjusted that the nails passed through them will enter the top of the tub or bucket equal distances apart, as shown in Fig. 2, or said nails may be differently spaced, 20 as desired, the adjustability of the driver-brackets 17 on the cross-head 16, the brackets 26, and the chuck permitting the operation upon tubs varying greatly in size. The drivers 11 are of course movable with the chucks 25 when adjusted and are permitted to slide freely in the driver-brackets 8 and 13, as will be understood.

The tilting nail-pan 40 is provided, as usual, with a slotted bottom, the slots therein coöperating with the nail-channels formed between the inclined track-plates 44, secured to the machine head or casting 43, said track-plates being adjustable, if desired, by bars 50 to vary the widths of the nail-channels; 30 but as this forms no part of my present invention the nail-channels may be of any suitable construction.

The nail-pan may be tilted at intervals or continuously by suitable mechanism—such, 40 for instance, as shown in my prior patents—and will operate to deliver nails into the upper ends of the nail-channels between the plates 44 and 45, as will be understood.

The devices for picking off or selecting the 45 nails from the lower ends of the nail-channels may be of any suitable construction; but I prefer to employ devices substantially as shown in my prior patent, No. 586,711, 60 indicating the disks, having notches 61 at their edges and rotated by worm-wheels 62 on studs 63, meshing with a worm 64, driven by gearing 65 from a shaft 66, connected with a suitable power-shaft at the lower portion of the machine. The nails in the channels are 55 picked off one at a time by the disks 60 and delivered into chutes 67, and from thence pass into spouts 68, which convey them into the chucks in the usual manner.

The manner of using and operating ma- 60 chines of this general construction is so well understood that no further description is deemed necessary.

By the employment of the cross-head and the cross-bar 16 shown and providing the adjustable driver and chuck brackets the 65 drivers and chucks may be adjusted to operate upon variously-shaped articles—baskets, tubs, or boxes—and when round articles, as tubs, are operated upon the extension 24 on the innermost chucks will serve to properly 70 center them when they are placed upon the work-support and moved back.

I claim as my invention—

1. In a nailing-machine, the combination 75 with the main frame, the work-support and the vertically-movable cross-head, the laterally-adjustable arms 8 on the cross-head, the driver-brackets adjustable longitudinally of the arms, and the drivers carried by the brackets and arms and adjustable thereon, the cross-bar 16 on the main frame, the brackets 17 adjustable thereon, the laterally - extending brackets 26, and nail-holding chucks adjustable upon the brackets 17 and 26. 80

2. In a nailing-machine, the combination 85 with the main frame and work-support, a cross-bar such as 16 on the frame, a pair of relatively adjustable chuck-supporting brackets on the bar, chuck-supporting brackets extending laterally from the last-mentioned 90 brackets and adjustable thereon, and nail-holding chucks adjustably secured to each of said brackets, of nail-drivers operating in the chucks, and means for operating them.

3. In a nailing-machine, the combination 95 with the main frame, the work-support, the vertically-movable cross-bar, the relatively adjustable driver-brackets mounted on the cross-bar having the slots in their lower sides, the driver-brackets extending laterally of the 100 first-mentioned brackets and adjustable thereon toward and from the cross-bar on the frame and the drivers adjustable on their brackets, of the nail-chucks supported below the driver-brackets and with which the drivers 105 coöperate and adjustable on their supports.

4. In a nailing-machine, the combination with the main frame and the cross-bar 16 thereon, of a pair of forwardly - extending chuck-supports secured to and adjustable 110 upon said bar, a pair of laterally-extending chuck-supports mounted upon the supports on the bar and adjustable longitudinally thereon, nail-holding chucks mounted adjustably upon the supports, two of said chucks 115 having the downwardly-extending arms for centering the work, and nail-drivers operating in the chucks and adjustable with the chucks.

HENRY W. MORGAN.
